METHOD AND MEANS FOR SILENCING
SQUEAKY WOODEN FLOORS

Thomas Irwin Lang, Mount Vernon, N. Y.

Application July 20, 1932, Serial No. 623,572

17 Claims.

(Cl. 20—6)

My present invention relates to an improvement in methods and apparatus for silencing squeaking finished wooden flooring, and has for its important object, the provision of means and methods for treating the cracks in such flooring whereby to provide the edges of the boards adjacent to and forming said cracks with a liquid, sound eliminating or silencing medium, which after evaporation of the solvent therein leaves a layer of squeak 5 eliminating coating on and between the coacting or cojoined board edges.

As is well known, wooden floors, especially of hard woods such as oak, and the like, in parquet or straight laid floors, even if well laid and nailed, 15 tend in time to shrink by drying out, and also to warp, thereby pulling loose from the fastening or nailing, so that when they are tread upon, annoying squeaks develop.

Subsequent re-nailing of such flooring seldom 20 cures the fault, as in a short time the warped, dried out flooring gradually pulls loose again and resumes the objectionable squeaking.

By my present method, the boards at their loose, warped portions, are treated through the 25 cracks thereof, and thereafter, no matter how great or imperceptible the spring of the warped portions, they are completely silenced.

These and other capabilities will be apprehended as the herein description proceeds and 30 it is obvious that modifications may be made in the formula or the apparatus herein disclosed without departing from the spirit hereof or the scope of the appended claims.

In the drawing, 35 Fig. 1 is a side view of the means for applying liquid to a flooring, such means being partly fragmented for convenience in showing;

Fig. 2 is a side elevation of the crack tracking means;

Fig. 3 is an end view thereof;

Fig. 4 is a plan view thereof; and

Fig. 5 is a transverse sectional view of a characteristic wood flooring of the tongue and groove type, showing the cracks therein, amplified 45 through shrinkage.

In the use of my device and method, I provide a thin non-viscous solution of a mixture hereinafter to be given in detail, which when applied to the exposed cracks 11 in a flooring 10, 50 Fig. 5, will, by capillarity, and surface tension be carried down into and spread along the adjacent edge surfaces of the boards. Such a fluid must be of extremely low viscosity, but must carry sufficient non-volatile material in solution to remain 55 as a substantial, residual squeak preventing coat-

ing, after the volatile fluid has evaporated away from the treated edges.

The squeak preventing or eliminating materials when dissolved in the volatile fluid carrier, must of themselves be of a low viscosity and volatility, 5 with an ability to readily flow into the cracks of, and spread along the edge surfaces of the boards to which the solution is applied.

Further, such squeak preventing material, as I apprehend it, and as it works out in practice, 10 must have two outstanding functions, one of which is to be partially absorbed by the pores of the wood to act as a lubricant, and the other to remain as a buffer or cushion upon the surfaces of the treated parts. 15

In practice I have found that one such solution, having all of the above desirable features, including the feature of being applicable to wood floors of extremely light color, without stain, is a mixture of benzene or naptha as a liquid vehicle 20 of low viscosity and readily evaporative qualities, and as a common solvent for a squeak eliminating mixture of paraffin and liquid rubber.

Such a solution, has been found extremely efficient for the purpose where the parts of mixture by volume are as follows; benzene or naptha, two and one quarter parts, paraffin one quarter part and liquid rubber, one part. 25

The liquid rubber may be made by dissolving caoutchouc in a solvent such as benzol or carbon 30 bisulphide to a point of saturation, when it is then ready for use.

In order to make the foregoing materials into a stainless, non-precipitating solution of suitable quality for the purpose herein denoted, the benzene or naptha is first heated to the melting point of the paraffin, then the paraffin is introduced and by stirring or shaking is thoroughly dissolved. 35

In denoting benzene or naptha, as the fluid 40 vehicle, it is to be pointed out that carbon bisulphide, benzol, napthol or carbon tetrachloride may also be substituted for the same purpose.

After the paraffin has been thoroughly incorporated and dissolved, then the rubber solution is added, and the solution well shaken and stirred until it is thoroughly incorporated. The solution after cooling is then ready for application to the floor. The mixture as above outlined makes an amber clear non-staining solution, with 45 no tendency of precipitation when allowed to stand. 50

In order to apply my solution to floors, reference may be had to the drawing, in which, in Fig. 1, there is shown, a solution container 2, 55

broken at its middle for convenience in showing, in which the fluid solution described is carried.

The lower end of the container 2 is provided with an extended spout 4, and a rubber compression bulb 1 is attached to the other end of the solution container 2 at 3.

As described, compression of the bulb 1, expels an amount of solution through the lower open end of the spout 4, at 5.

10 In order to locate the open end 5 of spout 4 and to hold it centrally to the crack while expelling solution from spout 4 while drawing the device along a crack, such as 11, Fig. 5, the lower end of spout 4 is provided with a tracking device or extension, generally denoted by 6, Figs. 1, 2 and 3.

15 In the form shown, the tracking means comprises a curved portion 6, having a curled, spout engaging means 7 which conforms to the diameter of the spout 4 at the point of attachment, 20 and may be soldered thereto, at or adjacent to the angled spout end 5.

25 At substantially right angles to the curl 7 and at the opposite end of extension 6 is located a right angled bent flange or runner 8, and on its outer edge is a down bent short crack entering flange 9.

30 As indicated in Fig. 2, the ends of the runner and flange 9 are upturned as at 14—14 for ease in sliding the attached tracking means to and fro when placing solution in a crack. As indicated by the dot and dash axis line A—B, Fig. 3, the spout end 5 is so located in the tracking means that the axis of the spout end 5 coincides with axis A—B, so that the crack flange 9 is in central alinement with the open spout end 5 when 35 the device is registered in a crack, so that expelled solution from open spout end 5 is directly introduced in the open crack when the device is positioned as illustrated in Fig. 1, where the crack flange 9 is shown dotted.

40 The operation of application of the solution is as follows, the container 2 is filled with the solution, the crack flange 9 entered into a crack, the implement comprised of parts 1, 2, 4 and 6 is then moved along the crack to be treated, and, 45 simultaneously, the bulb 1 is squeezed, to expel a continuous discharge of solution from spout end 5 into the crack, where, by capillary action it is immediately drawn into said crack as illustrated by the heavy lines 11—11, between boards 10—10. 50 Fig. 5. In this latter action the solution follows the contours of the tongue and groove contours 12—13, and thus, after the solvent becomes evaporated, the pores of the wood and the faces of the adjacent edges are filled and coated with 55 a lubricant and a squeak silencing cushion, which does not dry out.

60 The application of the cold solution, to floor cracks at points on the floor where warping and consequent squeaks are developed, is rapid, clean, effective and is far superior to renailing such loose places, because, in time the nails pull loose and the squeak is accentuated.

65 By the present method and treatment the desired results are economically and permanently accomplished and the residual silencing coating in the cracks and in the pores of the wood remains permanently active.

Having thus described my invention what I claim is:

70 1. A method of silencing floor squeaks in a laid wooden flooring having cracks therein consisting of treating the squeaking portions thereof, through the associate cracks thereof with a solution comprising paraffin and rubber dissolved 75 in a fluid volatile solvent.

2. A fluid for silencing squeaky portions of wooden flooring consisting in volume, of two and one quarter parts of a low-viscosity, volatile solvent fluid, one quarter part of paraffin and one and one quarter parts of dissolved rubber. 5

3. In combination, a floor having adjacent faces of adjacent boards coated with a mixture of one part of paraffin to five parts of rubber.

4. In combination, a floor having adjacent faces of adjacent boards coated with a dry, non-greasy, cushioning anti-squeak coating including a molecular mixture of paraffin and rubber. 10

5. In combination, a floor having adjacent boards and tongue and groove joints between said boards and a dry, transparent, non-sticky, non-greasy, cushioning anti-squeak coating in said joints from top to bottom, and end to end thereof, 15 said coating including a molecular mixture of one part of paraffin to five parts of rubber.

6. In combination, a floor having adjacent faces of adjacent boards coated with a dry, cushioning anti-squeak coating including a molecular mixture of paraffin and rubber said mixture being free of sticky substances and free of non-volatile oils which would grease the floor. 20

7. A method of silencing floor squeaks in a laid wooden flooring having cracks therein consisting of treating the squeaking portions thereof through the associate cracks thereof with a solution including paraffin dissolved in a fluid volatile solvent. 25

8. A method of silencing floor squeaks in a laid wooden flooring having cracks therein, consisting of treating the squeaking portions of said flooring through the cracks thereof with a squeak silencing fluid including rubber dissolved in a fluid volatile solvent. 30

9. A method of silencing floor squeaks in wooden flooring having tongue-and-groove connections forming cracks, said method comprising introducing into said cracks and all squeaking portions thereof a fluid solution comprising a low viscosity volatile solvent containing a dissolved non-drying surface coating anti-squeak material, 35 said solution passing to said portions by capillarity because of said low-viscosity. 40

10. A method of silencing floor squeaks in a laid wooden flooring having tongue-and-groove cracks therein, said method consisting in introducing by capillarity to the squeaking portions of 45 said cracks, a low-viscosity solution of lubricant and cushioning material dissolved in a low-viscosity fluid volatile solvent. 50

11. In combination, a floor having adjacent faces of adjacent boards coated with a non-greasy mixture of rubber and a lubricant. 55

12. In combination, a floor having adjacent faces of adjacent boards coated with a non-greasy, anti-squeak coating including an intimate mixture of paraffin and a cushioning material. 60

13. In combination, a floor having adjacent faces of adjacent boards coated with a mixture of paraffin and rubber.

14. A fluid for silencing squeaky portions of wood floors, comprising a non-volatile squeak silencing substance such as rubber and paraffin dissolved in a quickly volatile solvent the proportions of said solvent and substances being such that the fluid is thin enough to be quickly drawn into a floor crack by capillary action, and the substances are concentrated enough to silence squeak, said fluid being free of dirty, greasy and friction forming materials. 65

15. A silencing fluid for squeaky floors, comprising a cushioning substance and a lubricating 70 75

substance dissolved in a quickly volatile solvent, the proportions being such that the fluid is thin enough to be quickly drawn into a floor crack by capillary action, and the substances are concentrated enough to silence squeak after the solvent evaporates, said fluid being free of dirty, greasy and friction forming materials.

5 16. A fluid for silencing squeaky portions of wood floors, comprising non-volatile squeak silencing and cushioning substances dissolved in a quickly volatile solvent, said substances comprising about 40% of said fluid, whereby the fluid is thin enough to be quickly drawn into a floor

crack by capillary action, and the substances are concentrated enough to silence the squeak after the solvent has evaporated.

17. A silencing fluid for squeaky floors, comprising paraffin and rubber dissolved in a quickly volatile solvent said paraffin and rubber comprising about 40% of the fluid, whereby the fluid is thin enough to be quickly drawn into a floor crack by capillary action and the rubber and paraffin are concentrated enough to silence squeak 10 after the solvent evaporates.
